DESIGN FOR A HANDBAG OR SIMILAR ARTICLE

Irving Pichel, New York, N. Y.

Application January 23, 1941, Serial No. 98,334

Term of patent 3½ years

To all whom it may concern:

Be it known that I, Irving Pichel, a citizen of the United States of America, residing in New York, county of New York, and State of New York, have invented a new, original, and ornamental Design for a Handbag or Similar Article, of which the following is a specification, reference being had to the accompanying drawing, forming part thereof.

Fig. 1 is a front perspective view of a handbag or similar article showing my new design.

Fig. 2 is a rear perspective view thereof.

The dominant feature of my design resides in the portions shown in full lines.

I claim:

The ornamental design for a handbag or similar article, as shown and described.

IRVING PICHEL.
